ELLIPOGRAPH WITH GUIDE

Walter W. Scott, Denver, Colo.

Application October 7, 1950, Serial No. 188,981

3 Claims. (Cl. 33—31)

1

This invention relates to improvements in ellipsographs with reference more particularly to guides for the same.

This invention relates to an improved guide or holder for disk ellipsographs of the type shown and described in U. S. Patent 2,468,320 of April 26, 1948.

It is the principal object of this invention to produce a guide or holder for ellipsographs of the type having two relatively adjustable circular disks of the type shown in the above identified patent.

In order that an ellipsograph of the type mentioned may be conveniently operated, it is desirable to have the disks mounted in a guide or frame in which each disk revolves in its own bearing, which at the same time is constrained to a rectilinear movement at right angles to the other disk, the extent of the two movements being determined by the size and eccentricity of the disks.

The invention will be most readily understood when reference is had to the accompanying drawing in which the invention is illustrated in its preferred form, and in which:

Figure 1 is a top plan view of the assembly and shows the manner of supporting the disks for rotation and guiding them along rectangular axes;

Figure 2 is a section taken on line 2—2, Figure 1;

Figure 3 is an end elevation looking through plane 3—3, Figure 1;

Figure 4 is a section taken on line 4—4, Figure 1;

Figure 5 is a fragmentary section taken on line 5—5, Figure 1;

Figure 6 is a section similar to that shown in Figure 4 showing a slight modification;

Figure 7 is a diagrammatic representation of the two circular disks showing them adjusted to scribe the ellipse shown by broken lines; and

Figure 8 is a view similar to that shown in Figure 7 showing the disk assembly turned through 90 degrees.

Referring now to the drawing, reference character X designates the horizontal arm of a rectangular guide whose other arm has been designated by reference character Y, the point of intersection being designated by reference character O. These two arms are in the nature of rectangular coordinate axes, and may be positioned in the right angle between the two arms of a drafting machine when the ellipsograph is in use. In the embodiment shown, arms X and Y

have considerable width and are provided at the intersection with a rectangular projection 10 and at their ends with upwardly extending flanges 11 and 11'. Metal rods 12 and 13 are positioned 5 between flanges 11, 11' and projection 10 in the manner shown quite clearly in Figure 1. A plate 14 is provided at its ends with two flanges 15 and 16 that project upwardly and are perforated for the reception of guide rod 12. Plate 14 extends inwardly to a point a short distance beyond the inner edge of arm X and has cemented or otherwise attached thereto a plate 17 which has a circular inner bearing surface 18 and terminates at point 19 as shown in Figure 1. A circular disk 15 A is positioned in the arcuate loop or opening in plate 17 and the concave surface of the latter has a V-groove like that designated by reference numeral 20 in Figure 5. The periphery of disk A is transversely V-shaped and fits groove 20 so that the two parts interlock in a manner to permit relative rotation and prevent disk A from accidentally falling out of its bearing. A plate 21, which is somewhat similar to plate 17, is positioned to rest on the upper surface of arm Y 20 between it and guide rod 13. Plate 21 is provided with projections 22 and 23 that are perforated for the reception of guide rod 13. Plate 21 projects outwardly and has an arcuate loop whose extent is greater than 180 degrees in which disk B is mounted for rotation. From Figure 5 it will be seen that the concave surface of the loop or opening in plate 21 has a V-groove with which the correspondingly shaped edge of disk B cooperates. It will now be seen that disk 25 A is carried by plate 17 and mounted for rotation therein, the circular loop or recess in which it is mounted extending more than 180 degrees so as to hold it from accidentally falling out of its bearing. Disk B is similarly mounted, and the two disks with their bearings are movable along right angularly related paths.

Disk A is provided with a diametrical opening or slot 24 which, in the embodiment illustrated, has been shown as extending equal distances 45 from opposite sides of the center line of the disk, but which may extend principally from one side of the center line if desired. Disk B is provided with a diametrical slot 25 of substantially the same width as slot 24. A screw 26 having an enlarged flat thin head 27 extends through both slots 24 and 25 in the manner shown in Figure 4 and is provided with a clamping nut 28. By means of this screw the tension disks may be clamped in adjusted position and held against 50 relative rotation by friction. The unthreaded

portion 29 of screw 26 may be rectangular and of a size to fit the groove snugly and will thus serve to positively prevent the disks from rotating relative to each other. A scribe having a holder 30 from which a lead 31 projects is attached to screw 26 by means of a cylindrical projection 32 attached to the screw and an arm 33 extending from the scribe and passing through an opening in part 32. A set screw 34 serves to clamp the scribe in adjusted position. In Figure 6 a 10 slightly modified construction has been shown in which the scribe, instead of being attached to screw 26 by the means shown, is clamped in position by means of a nut 35.

Referring now more particularly to Figure 7, line 36 designates the diameter of disk A and line 37 designates the diameter of disk B, the centers of the two disks being respectively C₁ and C₂, while the point where the lead is positioned has been designated by P. In setting the scribe with relation to the two disks and with relation to the axes of the ellipse that is desired to be scribed, the distance from the center of disk B to point P is taken equal to one-half the minor axis of the ellipse and the distance from P to the center line of disk A is taken as equal to one-half the major axis of the ellipse. With the proper relation of the disks and the lead or scribe point selected and the two disks held against relative rotation or transverse movement, they are then rotated over the paper on which the ellipse is to be drawn. It will be seen from the drawing that disk A rotates with its periphery a fixed distance from guide rod 12, and if it moves longitudinally its center C₁ moves in a straight line. Disk B similarly rotates with its center a fixed distance from guide bar 13 and can move parallel with this bar. Since the two disks are clamped in eccentric relation, it is evident that when the two disks are rotated there will be a simultaneous movement of the disk centers parallel to their respective guide axes, and since the scribe or pencil point is positioned eccentrically with respect to the two disks, it follows that it will scribe an ellipse. The operation of the two disks is similar to that shown and described in the patent above identified. Applicant claims no invention in the two disk ellipsograph shown in Figures 7 and 8, but limits his claims to novelty to the holder shown in Figures 1 to 6, inclusive.

By rotatably securing the disks to holders in which they are rotatably connected and mounting the holders for movement along rectangular axes an assembly is produced that can be conveniently operated, either by positioning arm X against a T-square and holding it from longitudinal movement thereon during the time the disks are rotated, or by positioning the assembly in the inside angle of a drafting machine having right angularly related arms.

In the drawing the disks are connected with their respective bearings or holders by means of V-shaped grooves and projections. This, however, may be replaced by any other suitable means if reason is found for substituting other bearings.

In the embodiment illustrated and described the parts have been made from a suitable plastic with the exception of guide rods 12 and 13, the clamping screws and the scribe. However, any

other suitable material may be employed. It is, of course, possible to construct the entire device from metal such as aluminum, and applicant therefore does not desire to limit himself to any particular material. It is also possible and practicable to substitute for the guide bars 12 and 13 dove-tailed slots and projections or any other suitable guide means if such a change should be deemed advantageous.

Having described the invention, what I claim as new is:

1. In an ellipsograph of the type having two circular disks of different diameters assembled in eccentric superposed relation and held against relative rotation, there being a scribe point positioned in the diameter of greatest eccentricity and so located that its distance from the center of the larger disk is one-half the major axis and its distance from the center of the smaller disk 15 is equal to one-half the length of the minor axis; a device for supporting and guiding the disk assembly for rotation and constraining the two disks to move with their centers in straight right angularly related paths, comprising a member 20 having two right angularly related arms, plates positioned for movement in the plane of the upper surface of each arm, means for attaching the plates to their respective arms for right angular longitudinal rectilinear movement, each plate having an arcuate bearing surface of more than 180 degrees, one of said plates being in a plane below the other, the radius of curvature of the bearing surface in the lower plate being the same as the radius of the larger disk and the 25 radius of curvature of the bearing surface in the upper plate being the same as the radius of the smaller disk, the disks being positioned in their respective bearings, whereby when the disks are 30 clamped in eccentric position and rotated as a unit, the bearing plates will constrain them to move with their centers moving simultaneously 35 in right angularly related paths.

2. A guide device in accordance with claim 1 in which each arm carries a guide rod positioned 40 above the plate and in which the latter has spaced bearings through which the guide rod projects and along which the plate moves, the two guide rods being right angularly related.

3. A guide device in accordance with claim 1 in which the upper surfaces of the arms lie in the same plane and in which the plate having the larger bearing is positioned underneath the other plate and in which that part on top of the guide arm is offset from the part having the bearing the thickness of the plate whereby the upper surface of the part having the bearing will be in the plane of the upper surface of the corresponding arm.
